UNITED STATES PATENT OFFICE.

WILLIAM C. MICHAEL, OF CLAREMONT, NEW HAMPSHIRE.

CLASP.

949,938.

Specification of Letters Patent. Patented Feb. 22, 1910.

Application filed October 13, 1908. Serial No. 457,459.

To all whom it may concern:

Be it known that I, WILLIAM C. MICHAEL, a citizen of the United States, residing at Claremont, in the county of Sullivan and State of New Hampshire, have invented an Improvement in Clasps, of which the following description, in connection with the accompanying drawings, is a specification, like numerals on the drawings representing like parts.

My invention relates to clasps and more particularly, though not exclusively, to garment clasps, the particular embodiment thereof being herein shown as consisting of a clasp intended for use in connection with a hose supporter.

My invention will be best understood by reference to the following description when taken in connection with the accompanying illustration of one specific embodiment thereof, while its scope will be more particularly pointed out in the appended claims.

In the drawings: Figure 1 is a plan of a hose supporter clasp embodying one form of my invention; Fig. 2 is a side elevation of the same clasp with the jaws open; Fig. 3 is a similar view in section; Fig. 4 is a similar sectional view with the jaws closed; Fig. 5 is a view similar to Fig. 4 illustrating its utility in connection with garments of extra thickness; Fig. 6 is a sectional elevation of a modified form of clasp; and Fig. 7 is a detail in plan of the lower jaw of the clasp shown in Fig. 6.

Referring to the drawings and more particularly to Figs. 1 to 5, while my invention may be embodied in various constructions and forms, the one therein disclosed is provided with a fixed metallic base or jaw carrying member 1, and a movable metallic jaw carrying member 2, between which, as represented in Fig. 5, the stocking or other garment is adapted to be gripped.

The rear of the base member herein is provided with an elongated eye or loop 3 to receive the usual strap, although suitable provision may be made for securing the same to cords or any other desired connections, as conditions may require. At the jaw carrying end the base member 1 is provided with the upturned projecting portion 4 which, in the present case, is pressed up out of the metal of the base. The cooperating movable jaw member 2 is provided with an

opening 5 which, with the jaw depressed (Fig. 4), registers with and receives the upturned projection 4 of the fixed jaw, sufficient clearance being left between the projection and the opening to receive more or less of the material of the stocking or other garment, so that the same is frictionally held between the two jaws with a firm grip.

To increase the grip of the jaws upon the material of the garment, the projection 4 upon the fixed jaw is preferably surrounded by a body 6 of friction material, such as rubber or the like, and, when the jaws are closed, the flat under face 7 of the movable jaw is caused to overlie the surface of the friction material and compress the material of the garment against the same, thereby imparting an effective friction grip to the clasp. The edges of the base 1 adjacent to body 6 of friction material are preferably turned up and against the said friction material as at 8 to retain the latter in place.

To close the jaws there is provided suitable clamping means, herein in the form of the locking member or lever 9, pivoted at 10 in the upturned sides of the base member and having a cam portion 11 adapted to engage with a depression or bend in the outer face of the movable jaw carrying member 2. The proportions of the locking lever and the jaw carrying lever are such that, when the locking lever is turned to the position shown in Fig. 4, it closes the jaws and locks them in closed position while the outer end of the locking lever overlies the opening 5 in the movable jaw and the exposed portion of the garment thereat.

The clamping lever is preferably designed to clamp the movable jaw into firm gripping relation with the fixed jaw member, as represented in Fig. 4, however thin the intervening garment may be. In case, however, the clasp is called upon to grip material of unusual thickness, yielding means are preferably provided whereby the clamping lever is permitted its full clamping movement irrespective of the thickness of the garment.

While this may be accomplished in various ways herein I have provided means whereby, when the movable jaw comes to rest in gripping engagement with the garment, further movement of the clamping means to its final position results in depressing the opposite end of the jaw lever. Here-

in this is accomplished by providing a yieldable take-up between the locking lever and the jaws adapted to take up the surplus movement of the locking lever after the jaws have gripped, without deformation of the movable jaw carrying member. Herein such yieldable take-up consists of a spring 12 interposed between a seat 13 on the base and a seat 14 on the under side of the jaw lever, which spring tends to force the rear end of the jaw carrying lever against its fulcrum seat. Such seat may be provided by various means but herein it is provided by an elongated slot 15 arranged transversely in each upturned side of the base and adapted to receive each an outwardly turned lug shaped portion 16 on the jaw lever, each of which is adapted to work and seat in its respective slot.

Normally, as represented in Figs. 2 and 3, the spring 12 forces the fulcrumed end of the lever into its seat in the slot 15. When, however, the clamping lever is turned down to the position shown in Fig. 4 the jaw lever is swung about its fulcrum seat against the compression of the spring 12 until the movable jaw meets and grips the garment. This preferably takes place before the clamping member has completed its movement, so that further movement thereof merely tends to compress the spring and withdraw the fulcrumed end of the jaw lever from its seat in the slot 15, causing it to assume, for example, some such position as is shown in Fig. 5.

It will be obvious that the above described construction provides for a garment clasp which is adapted to grip the garments of varying thicknesses with the same tension, determined in each case by the spring 12.

My invention, so far as it relates to the last described feature, is in no wise limited to the particular construction of clasping jaws shown in Figs. 1 to 5. In Figs. 6 and 7 I have illustrated a different jaw construction. Herein the lower or fixed jaw is provided with a body 17 of rubber or other friction material suitably secured to the said jaw member, having one or more transverse grooves 18 preferably arranged to register with a transversely projecting portion 19 carried by the movable jaw member 20. In this form of jaw the garment is gripped directly between the movable jaw and the friction material and the fixed jaw, the grooved portion of the friction material preventing the slippage of the garment.

While I have shown and described one form of my invention for the sake of illustrating one concrete embodiment thereof, it is to be understood that the same is not limited thereto, but that extensive variations may be made in the construction and form and arrangement of parts there shown without departing from the spirit of the appended claims.

Having thus described my invention, what I claim is:

1. A clasp having coöperating fixed and movable non-flexing jaw carrying members, a movable locking member to lock the jaw carrying members about the material to be gripped, and a yieldable take-up interposed between the locking member and the jaws to take up the surplus movement of the locking member after the jaws have gripped without substantial deformation of the movable jaw carrying member whereby the locking member is permitted to execute its full clamping movement, irrespective of the thickness of the material to be gripped. 75

2. A clasp having a movable jaw-carrying lever, a coöperating jaw-carrying member, a fulcrum seat for the said lever, resilient means to press the lever against its seat, and means to force the lever about its fulcrum seat to close the jaws, said lever being permitted to withdraw from its fulcrum seat against the pressure of said resilient means on further application of the said jaw closing means after the closure of the jaws. 80

3. A clasp having a base member provided with a fixed jaw, a movable member carrying a coöperating jaw at one end, means on said base member providing a fulcrum seat for the opposite end of the movable member, a spring between the base and the movable member to force the latter against its fulcrum seat, and a cam lever pivoted on the base and adapted to engage the back of the jaw-carrying member and move the latter about its fulcrum to close the jaws, movement of the cam lever subsequent to such closure acting to withdraw the fulcrumed end of said member from its seat against the spring. 95

4. A clasp provided with a pair of coöperating jaws, one being provided with a body of rubber or other friction material surrounding a projection of relatively stiffer material, and the other provided with an opening adapted to receive the said projection, and a face adapted to overlie the said friction material. 100

5. A clasp having a fixed jaw, comprising a metallic base member having a metallic projection, a body of friction material resting upon said base member and surrounding said projection, and a movable jaw comprising a metallic plate adapted to overlie the said friction material and provided with an opening adapted to receive the said metallic projection. 115

6. In a clasp, the combination with a jaw-carrying member and a coöperating jaw-carrying lever, of a cam member for moving the jaw-carrying lever to close the jaws, and resilient means for automatically opening the jaws when released by the cam lever, said means also serving as a resilient abutment permitting the jaw carrying lever mov- 120

ably to fulcrum about the point of application of the cam lever.

7. A clasp having a jaw-carrying member and a coöperating jaw-carrying lever, said member being provided with wall portions presenting one or more slots, the end of said slot or slots presenting a fulcrum seat for said jaw-carrying lever, and means for forcing the said lever into clasping engagement 10 with the jaw-carrying member about its fulcrum seat in said slot.

8. A clasp having coöperating jaw-carrying members, one provided with slotted wall portions and the other fulcrumed in the 15 slotted end of said wall portions, means for closing said jaw-carrying members, and a spring for opening the same when released, said spring also serving as a resilient abutment permitting an opening movement of 20 the jaw-carrying end of the movable jaw-carrying member when said closing means is applied.

9. A clasp having the jaw-carrying member 1, the jaw-carrying member 2, one of 25 said members being connected with the slot 15 and the other with the coöperating lug 16, the cam lever 9 located at one side of the

slot, and the spring 12 located at one side of the cam lever.

10. A clasp having a movable, non-flexing, 30 jaw-carrying member, a coöperating jaw-carrying member, a spring tending to open said jaws, clamping means to close the jaws against the yielding movement of the spring, the non-flexing jaw-carrying member being 35 further movable under the yielding of the spring after the closing of the jaws.

11. A clasp having a non-flexing, jaw-carrying member, a coöperating jaw-carrying member, a spring tending to open said 40 jaws, clamping means engaging said jaw-carrying member tending to close the same against the movement of the spring, and a fulcruming rest for the said member located at a different point in its length than the 45 point of application of said spring.

In testimony whereof, I have signed my name to this specification, in the presence of two subscribing witnesses.

WILLIAM C. MICHAEL.
